UNITED STATES PATENT OFFICE.

THEODORE ULMER AND GOTTLIEB ULMER, OF ALPENA, SOUTH DAKOTA.

HOIST.

Application filed May 9, 1928. Serial No. 637,782.

This invention relates to hoists and more particularly to electrically controlled hoists wherein the motor that operates the hoisting drum is movable with the gearing and drum, 5 providing an exceptionally small and compact article to facilitate the transporting of the same.

Another object of the invention is to provide a movable frame of a particular design 10 to support the motor and gearing, whereby the entire structure may be moved as a unit.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within 20 in the scope of what is claimed, without departing from the spirit of the invention.

Referring to the drawings:

Figure 1 is a side elevational view of a hoist constructed in accordance with the invention.

Figure 2 is a vertical sectional view through the device.

Figure 3 is a front elevational view of the hoist.

Figure 4 is a bottom plan view of the device.

Referring to the drawings in detail, the frame of the hoist includes a pair of spaced bars 5 which have their lower ends connected by means of the bar 6, the upper portions of 35 the bars being curved as at 7.

The members forming the frame are held in proper spaced relation by means of the shelf or plate 8, which may be secured to the bars in any suitable manner. Mounted on 40 the plate 8, is the motor 9 which may be supplied with electric energy from any suitable source of supply, opposed contact members 10 being provided however, to control the electric circuit not shown.

45 The upper portions of the bars 5 are covered by the plate 11 which is curved providing a hood for the frame as clearly shown by Figures 1 and 2 of the drawing, the hood also providing means for connecting the hook member 12 to the hoist, which hook member is designed to support the hoist.

Bearings indicated at 13 are mounted on the frame and support the shaft 14 that extends transversely of the frame, on which 55 shaft are mounted gears 15, the gears being

keyed to the shaft and disposed adjacent to the ends thereof. Keyed to the shaft 14 at a point between the gears 15 is a sprocket 16 over which the chain or flexible hoisting member 17 operates. Meshing with the gears 15 are pinions 18 disposed at the outer ends of the shaft 19, that operates in the bearings 20 which are also secured to the frame of the hoist.

60 Mounted to operate with the shaft 19 is a gear 21 disposed substantially intermediate the ends of the shaft 19, the gear receiving motion from the worm 22 supported at the outer end of the shaft 23, the extreme outer end of the shaft 23, operating in the bearing 24 that is secured to the frame by means of the bracket 25.

65 This shaft 23 also moves in the bearing 26 and carries the beveled pinion 27 at one end thereof, the beveled pinion meshing with the 70 pinions 28 and 29 that are loosely mounted on shaft 30 which constitutes the power shaft of the hoist.

75 As shown, hubs 31 of the pinions 28 and 29 are formed with clutch faces 32 to cooperate with the clutch faces 33 of the clutch member 34, which is splined on the shaft 30 so that by moving the clutch faces 32, the pinion 28 or 29 may be clutched to the shaft 80 to operate therewith. A clutch controlling 85 arm is indicated at 35 and has pivotal connection with the clutch member 34 at 36, or at a point intermediate its ends, the upper extremity of the arm 35 lying adjacent to the contact members 10 so that movement of 90 the arm 35 to operate the clutch member will simultaneously contact with one of the members 10 to complete the circuit to the motor to cause the operation thereof.

95 The clutch arm 35 is operated by means of the flexible member 37 that operates over the rollers 38 supported by the arms 39. Thus it will be seen that by a pull of the flexible member 37, the arm 35 will be operated in a manner as described.

100 Mounted at one end of the shaft 30 is a pulley 40 over which operates the belt 41 that also operates over the pulley 42, the pulley being mounted at one end of the armature shaft of the motor 9. In order that the belt 105 41 will be taut at all times, an idle pulley 43 is provided, which is supported by the pivoted arm 44 and allows the weight of the pulley to be directed to the belt 41 to take up such slack as may be present therein, in a 110

manner as shown by Figure 1 of the drawings.

From the foregoing it will be seen that if it is desired to operate the hoist, the flexible member 37 is pulled, moving the arm 35 into engagement with one of the clutch faces of one of the beveled pinions 28 or 29.

As the pinion operates, the beveled pinion 27 is operated, which in turn directs rotary motion to the worm 22 through shaft 33.

As the worm 22 operates, the shaft 19 is operated, which transmits motion to the pinions 18 disposed on the ends thereof, which pinions 18 transmit motion to the gears 15, whereupon the shaft 14 is operated to rotate the sprocket wheel 16 for moving the hoisting member 17.

If it is desired to rotate the sprocket member 16 in the opposite direction, the arm 35 is moved from its active position to the opposite side of the shaft 30 where the clutch member cooperates with the opposed clutch

member of the pinion at the opposite end of the shaft.

Having thus described the invention, what is claimed as new is:—

In a portable hoist a frame including a pair of end sections, the upper portions of the end sections being curved, a curved cover plate connecting the end sections, each end section including a lower bar, a shelf supported between the end sections and defining a motor support, gearing supported by the frame, a motor on the motor support for operating the gearing and a hook member secured to the curved cover plate, and said hook member adapted to be positioned in a supporting eye.

In testimony that we claim the foregoing as our own, we have hereto affixed our signatures.

THEODORE ULMER.
GOTTLIEB ULMER.
